ROAD MAINTENANCE MACHINE

Loyd H. Adams, Waverly, Iowa

Application June 1, 1949, Serial No. 96,591

7 Claims. (Cl. 262—8)

1

This invention relates to improvements in road maintenance machines and more particularly has to do with an improved machine for removing ice and packed snow from highways. While my improved machine is especially adapted for the removal of ice and packed snow, the machine is also useful for various other road work including maintaining gravel roads and doing away with washboard, scarifying oil roads; for laying stabilized base materials, filling holes left by sheep foot rollers and to loosen borrow pits for new seeding.

Packed snow and ice on paving have presented quite a removal problem. The ordinary straight blade commonly employed for this purpose does not perform satisfactorily.

A primary object of the present invention is to provide an improved cutting blade unit adapted to be mounted on graders, tractors and trucks, and also for use with one-way and V snow plows.

The invention comprehends a cutting blade unit including a beam to be attached to a motor-propelled vehicle to extend transversely of the line of travel of the same, and a multiplicity of elongated rectangular shaped relatively narrow cutting blades specially arranged in close formation in a plurality of rows extending longitudinally of the beam to efficiently cut into, loosen, and remove ice and packed snow from a roadway.

Other objects of the invention are to provide a strong, sturdy cutting blade unit of the character referred to and to provide simple efficient means providing for rigidly and detachably mounting the cutting blades on the beam whereby the blades will be firmly supported on the beam and can be quickly mounted thereon and removed therefrom for replacement.

A further object of the invention is to provide efficient, compactly arranged means for mounting the cutting blade unit on a motor-propelled vehicle for vertical adjustment relative to the roadway.

The invention, with other objects, novel features, and advantages thereof, and the particular construction, combination and arrangement of parts comprising the same will be understood from the hereinafter contained detail description when considered in connection with the accompanying drawings forming part hereof and illustrating one embodiment of the invention.

In the drawings:

Fig. 1 is a side elevation of a motor-propelled truck having mounted thereon a cutting and scraping blade unit constructed in accordance with the present invention.

2

Fig. 2 is a detail fragmentary end elevation, on an enlarged scale, of the cutting blade unit and the supporting means therefor.

Fig. 3 is a detail perspective view on the lower part of one of the guide bars.

Fig. 4 is a detail horizontal section of the line 4—4 of Fig. 2.

Fig. 5 is a perspective view, to an enlarged scale, of the cutting and scraping blade unit supported on a truck, only part of the truck structure being shown.

Fig. 6 is a detail top plan view of the cutting blade unit.

Fig. 7 is a front elevation of the cutting blade unit.

Fig. 8 is a detail vertical section on the line 8—8 of Fig. 6.

Fig. 9 is a detail perspective view of one of the cutting blades.

Fig. 10 is a detail perspective view of one of the blade supporting plates with the reinforcing means therefor.

Fig. 11 is a horizontal section on the line 11—11 of Fig. 2.

25 While a preferred embodiment of the invention is illustrated in the drawings, it will be understood that minor changes and modifications may be made in the particular construction shown and the invention may be embodied in other forms as will appeal to those skilled in the art and falling within the scope of the appended claims without departing from the spirit of the invention.

Referring to a detail description of the particular embodiment of the invention illustrated in the drawings, the construction shown includes a cutting and pulverizing blade unit generally designated A mounted on a motor-propelled truck B of conventional construction, the cutting and pulverizing blade unit being disposed transversely of the line of travel of the truck.

35 The cutting blade unit A includes a channel beam of substantial width, the same having a main flat part or base 17, and straight side flanges 18. The beam, which is disposed with its chan-

nel facing upwardly, is relatively heavy and is reinforced at each side by a flange 19 extending inwardly from the side flange 18 substantially parallel with the base 17, and a flange 20 extending downwardly from the terminal marginal portion of the flange 19 to and joined with the base

45 17. Rigidly secured to the beam at the underside thereof are a multiplicity of elongated rectangular shaped relatively narrow cutting blades 21, said blades being shown as each having a substantially flat lower end face 22. While the blades 21 are of elongated form, the same are,

50 55

as shown in the drawings, of substantial width. The cutting blades 21 are arranged in close formation in two rows extending longitudinally of the beam with the blades of one row in staggered relation with the blades of the other row. The cutting blades are disposed at an inclination to the line of travel of the truck B. The blades of each row extend parallel with each other, and the blades of one row are disposed at an angle to the blades of the other row.

Means is provided for rigidly and detachably securing the cutting blades 21 to the beam comprising rectangular shaped plates 27 extending vertically downwardly from the underside of the beam and rigidly secured thereto by welding, one of said plates being provided for each one of the blades. The plates 27, which are rectangular shaped and of substantially the same width as the cutting blades 21, are each reinforced at the rear side thereof at each end by gusset blocks 28. The gusset blocks, which are shown triangularly shaped, fit against a side face portion of the plate and an adjoining bottom face portion of the channel and are joined thereto by welding. Each plate 27 is provided with a bolt aperture 29 intermediate its side edges between the gusset blocks 28, and each blade 21 is provided with a bolt aperture 30, each of the blades being adapted to be arranged with its upper end face fitting against the bottom face of the beam and an adjoining side face portion fitting against one of the plates 27, and being secured thereto by a bolt 31 and nut 32, the bolt passing through the apertures 29, 30, in the blade and plate. This special arrangement affords a firm, rigid mounting for the blades 21 on the beam and at the same time provides for quick and easy assembly of the blades on the beam and removal of the same therefrom for replacement. The beam, which is shown as substantially straight, may be constructed with any desired crown to correspond generally to the transverse contour of the roadway to be operated on.

The cutter blade unit A is supported on the truck B at the underside thereof for vertical adjustment by a pair of guide bars 33 slidable in vertical guides 34 on opposite sides 35 of the body of the truck B and connected at their lower ends to opposite end portions of the beam of the cutter blade unit. On the channel beam of the cutter blade unit at opposite end portions thereof, are upstanding tubular bosses 36, and each guide bar 33 is provided with spaced apertured horizontal lugs 37 projecting forwardly from the front side thereof. Each pair of the spaced apertured lugs 37 is adapted to straddle one of the tubular bosses 36 and the adjoining end portion of the beam as shown in Fig. 2 of the drawings, and the guide bar 33 is connected to the beam by a bolt 38 and nut 39, the bolt passing through the apertured lugs 37, one of the tubular bosses 36 and an aperture in the base 17 of the beam. The guides 34 on the sides 35 of the truck B each comprise a rear plate 40 and a front U-shaped plate 41 having attaching flanges 42 extending laterally from the outer ends of the leg portions thereof, the rear plate 40 and the attaching flanges 42 being secured to the side of the body of the truck by bolts 43.

Cooperating with the guides 34 and providing for the vertical adjustment of the cutting blade unit A, are a pair of hydraulic cylinders 44, one of the hydraulic cylinders being located at each side of the body of the truck B and suitably secured thereto, said cylinders being vertically

disposed. Each cylinder 44 is equipped with a piston 45 provided with a rod 46 extending downwardly from the lower end of the cylinder and having its lower end positioned between and secured to a pair of spaced vertical ears 47 on one of the vertical guide bars 33. 48 and 49 are conduits leading from the upper and lower parts of each of the hydraulic cylinders 44 to conventional control means (not shown) located in the 10 cab b of the truck B. As will be understood by regulating the pressure in the cylinders 44 at either side of the pistons 45, the cutting blade unit A can be moved vertically as desired to adjust the same with the cutting blades or teeth 15 21 in proper position to operate upon the roadway or to elevate the cutting blade unit out of operative position.

In the operation of the machine, the cutting blade unit A is adjusted vertically through the 20 hydraulic cylinders 44 to properly position the cutting blades or teeth 21 relative to the roadway to be treated. As the truck B moves forwardly, the multiplicity of closely associated cutting blades or teeth 21 cut into and effectively loosen the packed snow or ice, the loosened snow or ice being deflected laterally to one side by the first 25 row of cutting blades or teeth, and then to the opposite side by the second row of cutting blades or teeth, the special construction and relative 30 arrangement of the multiplicity of elongated relatively narrow rectangular shaped blades or teeth providing for a thorough loosening and scraping of the ice and packed snow from the roadway. The road maintenance machine as described 35 hereinbefore differs from the so called road scarifiers and road scrapers. In the road scarifiers the surface of the roadway is simply dug up by a toothed attachment to a vehicle and in most instances the scarifiers are of the floating type. 40 In other words, these scarifiers with the toothed attachments ride up and down on the uneven surfaces of the roadway and simply rip it up and in this ripping action the ripped surfaces of the roadway that are in rather large pieces or 45 chunks are irregular in size. When this scarifying action has been accomplished then it is necessary to employ a different type of pulverizing machine to render the large and irregular size pieces of substantially uniform size.

As regards the road scrapers, such machines usually embody therewith a single blade that is diagonally arranged with respect to the vehicle and this blade merely rips up the surface of the roadway or levels it off and there is no pulverizing action whatsoever.

In the present invention due to the particular arrangement of the elongated wide flat rectangularly shaped rigid cutting blades in two rows and with the spaces between the rows and each of the blades of the rows and the fact that the blades are in staggered relation and that the blades of one row are disposed in an opposite but substantially corresponding angle to the blades in the other row, the result of shearing cutting of the 60 roadway surface, and such surface may be ice or packed snow or a combination of both or the actual surface of the roadway itself such as a so called black top roadway surface or the surface may be earth or similar to macadam, is accomplished. The present roadway maintenance machine includes means for fixedly holding the two aforesaid rows of blades, once adjusted, relative to the vehicle to which the beam with the blades attached thereto is attached. This means 65 that the beam with the blades attached does not

float such as scarifiers do and the bottom edges of the blades of the present invention are therefore maintained in a proper position to effect a shearing cutting of the roadway surface and a fine pulverization of the surface, whether it be packed ice, packed snow or a combination of both or the actual roadway surface such as black top, etc. The necessity of further pulverization of the roadway surface is thus obviated because the particular blade arrangement as recited herein effects not only the shearing cutting but a fine pulverization thereof.

What I claim is:

1. A road maintenance machine including a motor-propelled truck, a cutting and pulverizing blade unit comprising a channel beam of substantial width having straight side flanges and reinforced at each side by a flange extending inwardly from the marginal portion of the side flange substantially parallel with the base of the channel, and a flange extending downwardly from the marginal portion of each of the last mentioned reinforcing flanges to and joined with the base of the channel, the beam being disposed with its channel facing upwardly, a tubular boss on one of the reinforcing flanges near each end portion thereof adjacent a side edge of the beam, a plurality of cutting blades on said beam at the underside thereof projecting downwardly therefrom, and means supporting said beam on the truck at the underside thereof including a vertical guide on each side of the body of the truck, and a vertical guide bar at each side of the truck slidably engaging one of said tubular guides, each of said guide bars having a pair of spaced apertured ears thereon projecting forwardly from the front side thereof and straddling one of said bosses and the adjoining end portion of the beam, and a bolt and nut connecting each guide bar with the beam, the bolt passing through one of the tubular bosses, through apertures in the beam and the pair of apertured ears on the guide bar.

2. A road maintenance unit comprising a beam to be attached to a vehicle for raising and lowering relative thereto and disposed transversely of the line of travel of the same, a plurality of elongated wide flat rectangular spaced rigid cutting blades with wide opposite side faces and each having an upper end fixedly secured on said beam at the under side thereof and depending therefrom, the lower end of each blade being flat and presenting a cutting edge throughout the width thereof, said blades being arranged relatively close together but having spaces therebetween in two spaced rows extending longitudinally of the beam with the blades of one row disposed at an oblique angle to the horizontal axis of the beam and in staggered relation to the blades of the other row, and the blades of the said other row being disposed at an opposite but substantially corresponding oblique angle to the blades in the said one row.

3. A road maintenance machine including a vehicle, a cutting and pulverizing unit comprising a beam to be attached to the vehicle and disposed transversely of the line of travel of the vehicle, a plurality of elongated broad flat rectangular rigid cutting blades having wide opposite side faces and each blade having an upper end fixedly secured on said beam at the under side thereof and depending therefrom, the lower end of each blade being flat and presenting a cutting edge throughout the width thereof, said blades being disposed relatively close together but hav-

ing spaces therebetween and arranged in two spaced rows extending longitudinally of the beam with the blades of one row disposed at an oblique angle to the horizontal axis of the beam and in staggered relation to the blades of the other row, the blades of the said other row being disposed at an opposite but substantially corresponding oblique angle to the blades of the first mentioned row, means supporting said beam on the vehicle at the under side thereof for vertical adjustment and disposed transversely of the line of travel of the vehicle, and means for vertically adjusting said beam to and maintaining the same in a fixed position relative to the vehicle with the cutting and pulverizing blades positioned to operate upon the roadway surface to shear cut and pulverize the same, and to elevate and hold the beam in a fixed position with the cutting and pulverizing blades out of operative position.

4. A road maintenance unit comprising a beam to be attached to a vehicle and supported therefrom transversely of the line of travel of the vehicle, front and rear rows of vertically disposed broad cutting blades projecting downwardly from said beam and having flat front and rear side faces and at their lower ends each having a straight transverse cutting edge extending its full width, the blades of each row being spaced from each other longitudinally of the beam and also spaced from the blades of the other row transversely of the beam and disposed in staggered relation thereto, the blades of each row being rectangular in horizontal cross section and disposed at an oblique angle transversely of the front side of the beam and extending in an opposite direction to the oblique angle of the blades of the said other row, mounting members for said blades consisting of a plurality of wide flat rectangular plates disposed vertically in flat face-to-face engagement with said blades and at their upper ends being rigidly secured to the underface of said beam and braced by webs extending rearwardly from opposite side edges of the plates, and fasteners passing through the plates and their companion blades, said blades extending downwardly beyond the lower ends of the mounting plates and each having at its lower end a straight transverse cutting edge extending throughout the width of the blade.

5. A road scraper unit comprising a beam to be attached to a vehicle and disposed transversely of the line of travel of the vehicle, said beam having a flat bottom face, a plurality of vertically disposed broad flat rectangular shaped cutting blades projecting downwardly from the under face of said beam, the blades being arranged in front and rear rows with the blades of each row in staggered relation to the blades of the other row, all of said blades being disposed in cross section at an oblique angle to the front side of the beam and the oblique angle at which the blades of each row extend being in a direction opposite to the direction in which the blades of the other row extend, and means detachably and rigidly securing said blade to the beam and retaining the said blades at the said oblique angles, said blades each having at its lower end a straight transverse cutting edge extending its full width.

6. A road maintenance machine including a truck, a cutting and pulverizing unit comprising a channel beam of substantial width extending under the truck transversely thereof and having upstanding flanges along front and rear edges reinforced by horizontal flanges extending in-

wardly from upper edges of the side flanges in upwardly spaced relation to the bottom of the beam, inner side edges of the horizontal flanges being spaced from each other transversely of the beam; and supported by inner side flanges extending downwardly therefrom and at their lower edges being united with the bottom of the beam and thereby providing the beam with hollow side portions extending longitudinally of the beam and spaced from each other transversely of the beam, a plurality of blades under said beam extending downwardly therefrom and arranged in front and rear rows disposed under said hollow front and rear side portions of the beam, the blades of each row being spaced from each other longitudinally of the beam and arranged in staggered relation to the blades of the other row, and means for suspending the beam from the truck and vertically adjusting the position of the beam.

7. A road maintenance machine including a truck, a cutting and pulverizing unit comprising a beam of substantial width extending under the truck transversely thereof, a plurality of blades under said beam extending downwardly therefrom and arranged in front and rear rows, the blades of each row being spaced from each other longitudinally of the beam and disposed in staggered relation to the blades in the other row, tubular bosses extending upwardly from opposite end portions of said beam adjacent the rear side edge thereof, and means supporting said beam under said truck including a vertical guide on

15

25

30

each side of the body of the truck, a vertical bar slidable vertically through each guide, each bar having upper and lower perforated ears projecting forwardly therefrom, the upper ears being disposed over said tubular bosses and the lower ears extending under the rear side portion of the beam; and bolts passing vertically through the ears and also through said beam and having nuts applied thereto to hold the bolts in place, and means for shifting said bars vertically through the guides and holding the bars in adjusted positions with the beam and said blades in a set position relative to the surface of a road along which the truck moves.
